ATTORNEY

UNITED STATES PATENT OFFICE.

JAMES E. GARVIN, OF BROOKLYN, NEW YORK.

LUGGAGE CARRIER.

Application filed March 8, 1927. Serial No. 173,621.

This invention relates to luggage carrying devices as applied to automobiles.

Such carriers are customarily secured to the running board, used as a step in entering and leaving a car, by bolts or like fastenings, which, due to the vibration of the car when operating, are prone to become loosened, causing annoyance from the sound engendered and not infrequently loss of parts including the article carried.

Moreover, the perforations in the running board are objectionable, as they tend to weaken the same and are unsightly.

It is therefore an object to provide an efficient device whereby luggage of any ordinary type may be safely secured on the exterior of a car without mutilating or disfiguring it.

A further feature is in the provision of one or more bars permanently fixed to the splash plate at a spaced distance outwardly therefrom to which straps or like flexible fastening means may be engaged, the weight of the luggage being taken preferably by the running board below.

Another purpose is in the production of a simple and inexpensive device, which may be relied on to perform its functions.

These advantages are attained by the novel and practical construction and arrangement of parts hereafter described and shown in the annexed drawing, forming part hereof, and in which:

Fig. 1 is a perspective view of a conventional type of automobile illustrating the application of an embodiment of the invention.

Fig. 2 is an enlarged top plan view of the device as applied to the splash plate of a car.

Fig. 3 is a transverse sectional view taken on line 3—3 of Fig. 2 and drawn to a further enlarged scale.

Substantially all types of cars are provided with running boards as indicated by the numeral 5, the same being used as steps in entering and leaving the car, and being at an ac-
commodating level.

Extending from the ends of the running board are mud guards 6 and 7, respectively over the front and rear wheels as shown.

A splash plate or guard 8 is attached to the inner edge of the running board 5 extending upwardly to join the body of the car by an inwardly curved member 9, just below the bot-

tom of the door, this splash guard reaching between the curved front and rear mud guards, which construction is typical and 55 illustrative only.

The invention consists in the application of a bar or rail 10, preferably of thin rectangular cross section, to the splash guard plate along its upper edge, parallel with the running board and at a considerable distance above it, the bar outstanding from the splash plate due to the interposition of spacing collars 11.

The bar is held at spaced intervals by bolts 12 passing through it and the spacers 11, to be engaged by nuts 13 at the back of the plate, these nuts being elongated to contact with the angular element 9 and thus are prevented from turning.

The article to be carried, as illustrated by a bag 14, may rest on the running board 5, the straps 15 which pass around the bar or bars 10 being secured by buckles 16 or other adequate fastenings whereby the article is firmly anchored.

This arrangement is adjustable to suit conditions and, as there are no parts to become loosened by shocks, jars, vibration, etc., positive security is attained and noise eliminated.

It is to be noted that notwithstanding the illustration shows the article of luggage as resting on the running board, certain articles, as for instance golf bags and like small packages, may be suspended by the straps alone 85 and rest against the face of the splash plate, free and clear of the running board at some distance above it.

It is further within the scope of the invention to provide two bars arranged in spaced 90 relation if considered desirable to do so.

From the foregoing it will be seen that a simple device for this purpose has been disclosed in the preferred form of its embodiment, but it is not desired to restrict the details to the exact instruction shown, it being obvious that changes, not involving the exercise of invention, may be resorted to without conflicting with the scope of the appended claim.

Having thus described my invention, what I claim as new and desire to secure by Letters Patent, is:

In a luggage carrying device for use on ve-

hicles provided with a running board, and a splash plate, having one curved end, the combination of the following elements; a bar secured in spaced parallel relation to the said splash plate; a plurality of luggage encircling elements adapted to pass through the space between the said splash plate and the parallel

bar secured thereto; and a series of bolts passing through said bar and said plate and provided with nuts adapted to be locked against turning by the curved end of the splash plate. ¹⁰

In testimony whereof I have hereunto affixed my signature.

JAMES E. GARVIN.
